CLAIM

(57) The ornamental design for a vehicle camera, as shown and described.

DESCRIPTION

FIG. 1 is a front, left, and bottom perspective view of a vehicle camera, showing my new design;

FIG. 2 is a rear, right, and top perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof; and,

FIG. 9 is a detailed view taken from encircled portion labeled "9" in FIG. 1.

The short-dash and long-dash broken lines in FIG. 1 denote the boundaries of the detail areas and form no part of the claimed design. The even broken lines in the figures are portions of the vehicle camera that form no part of the claimed design.
